UNITED STATES PATENT OFFICE

2,493,181

BABY BASKET

Arthur A. Andersen, Jr., Crystal Lake, Ill.

Application May 12, 1944, Serial No. 535,262

12 Claims. (Cl. 5—98)

1

The invention relates to a baby basket that may be used for several purposes. More particularly, the basket of this invention is adapted to be used as a crib, bath table, hammock, and auto basket.

One of the objects of this invention is to provide a basket having a fabric container portion and removable braces for securing said container in assembled position. More particularly, the fabric container is designed to provide corner pockets in which corner posts are mounted, and the braces cooperate with these corner posts to form a skeleton frame for the fabric container.

A further object of the invention is to provide a basket of the character above described in which the bracing means are foldable into a compact unit when not in use.

The invention further consists in the several features hereinafter described and more particularly defined by claims at the conclusion hereof.

In the drawings:

Fig. 1 is a perspective view of the baby basket embodying the invention;

Fig. 2 is a detailed vertical sectional view taken on the line 2—2 of Fig. 1;

Fig. 3 is a detailed transverse vertical sectional view taken on the line 3—3 of Fig. 1;

Fig. 4 is a detailed elevation view of one of the braces in folded condition, parts being broken away and parts being shown in section;

Fig. 5 is a plan view of the brace shown in Fig. 4, parts being broken away;

Fig. 6 is a detailed perspective view of one corner of the device looking into the interior, parts being broken away and parts being shown in section;

Fig. 7 is a detailed sectional view similar to Fig. 3 showing the device adapted for use as a bath table, parts being broken away;

Fig. 8 is a view similar to Fig. 3 showing the extension flaps in position when the device is used as a hammock;

Fig. 9 is a side elevation view showing the device when in use as a hammock;

Fig. 10 is a detailed side elevation view of a fastener that may be used for one of the hammock ropes;

Fig. 11 is a perspective view showing the device in use as an auto basket, parts of the automobile seat being shown in section;

Fig. 12 is a vertical sectional view similar to Fig. 2 showing certain modifications in the bracing;

2

Fig. 13 is a detailed sectional view taken on the line 13—13 of Fig. 12;

Fig. 14 is a detailed sectional view taken on the line 14—14 of Fig. 13;

Fig. 15 is a detailed view of a modified form of brace, parts being broken away and parts being shown in section;

Fig. 16 is a perspective view of a modified form of the device in use as an auto basket, parts being broken away;

Fig. 17 is a detail sectional view taken on the line 17—17 of Fig. 16 with parts in a folded position;

Fig. 18 is a detailed view of parts shown in Fig. 16.

The basket includes a fabric body or container portion preferably of heavy duck or canvas having a bottom 15, sides 16, and ends 17. The bottom is preferably secured to the sides and ends by stitching 18. Both sides have extension flaps 19, and both ends have extension flaps 20. These may normally be folded down within the inner walls of the container. Where the flaps 19 and the sides 16 join at the top, a lengthwise extending rope receiving pocket 21 is formed by stitching 22. The device is of generally rectangular shape, and at its corners pocket strips 23 are provided secured by stitching 24 to the sides 16 and ends 17, respectively. These strips 23 cooperate with the corner portions formed by the joining of the sides and ends to form post receiving pockets 25. Wooden or metal posts 26 extend through the pockets and project from opposite ends of the container, the bottom being cut out at the corners for this purpose. These posts are fixedly secured in the pockets by rivets 27 and washers 28. At their upper and lower ends each of the posts has recesses or slots 29 extending at right angles to each other.

Removable toggle link braces are adapted to be connected to oppositely disposed posts and act in conjunction with the posts as a spreader means to hold the fabric body covering in assembled position. As shown in Figs. 1 to 5, each brace means includes an angle bar 30 and a solid bar 31 pivotally secured together at 32, the inner end of the bar 31 adapted to rest within the angle of the bar 30, the ends of each of the bars being rounded as indicated at 33 so as to readily seat themselves in the recesses 29, the channel shaped bar having its end 33 formed by bending in parts of the sides of the channel as shown in Fig. 5. To hold these braces in aligned position a collar 34 is slidably mounted on the channel section bar 30, so that when moved past the pivot

32, it will also engage the solid bar 31 to hold the bars against pivotal movement and in a straight line position.

With this construction when the collar 34 is in a released position, the toggle links or bars 30 and 31 may be swung about their pivot 32 to an acute angle position, and then after the ends 33 are brought into alignment with the slots of the posts at the opposite ends of the body, these members 30 and 31 are moved to a straight line position and then locked by sliding the collar 34 over the bar 30 into the position shown in Fig. 2 under which conditions the bars because of their calculated length produce stretching pressure on the fabric sides of the body to hold it in an assembled position. These toggle braces brace both the opposite ends and the opposite sides of the structure at the top and bottom of the container, and in the structure shown in Fig. 1 they are positioned inside of the walls of the container. When not in use, the toggle braces may be folded up as shown in Figs. 4 and 5, so that the bar 31 nests within the channel of the bar 30 and is secured therein by the collar 34.

The fabric body may have fabric carrying handles 35 secured to its end portion by stitching 36 and in the assembled position shown in Figs. 1 to 3 forms a baby basket or crib.

When it is desired to use this basket as a bath table, one of the side flaps 19 is moved up to project from the top of the basket and is then extended across the top thereof and secured at its free end by snap or glove fastener connection 37 with the opposite side of the basket as shown in Fig. 7, the button portions 37' of these fasteners being secured to the upper edge of the side 16.

For converting the basket into a swinging basket or hammock, ropes 38 are run through the pockets 21 and secured at their ends to supporting hooks 39 as shown in Fig. 9, and for this purpose a connector 40 of the form shown in Fig. 10 may be used comprising a hook engaging metal ring 41 and a metal strap 42 pivotally connected at one end to said ring and provided with spaced rope receiving holes 43 through which the ropes 38 at the side of the basket may be passed to form a self-holding hitch.

In order to shield the infant within the basket from the weather, the side flaps 19 may be brought up to extend above the basket and be secured together by a cord or rope 44 secured to the hooks 39 and passing through gromets 45 in the outer edges of said flaps to form a tent top and as a wind break, one of the end flaps 20 may be brought up above the basket and be secured to the flaps 19 by passing the rope 44 through spaced gromets 46 in said flap 20 as shown in Figs. 8 and 9.

For mounting the basket in an automobile, ropes or cords 47 are passed through the pockets 21 and secured at their ends to spaced seat engaging hooks 48 or other suitable means for suspending the basket against a seat 49 of an automobile as shown in Fig. 11.

Instead of making the brace links as separate units for each side of the basket, they may be formed as a single collapsible unit as shown in Figs. 12 to 14, inclusive. In this instance each side brace includes a pair of toggle links 50 and 51 pivotally connected at their inner ends by a pivot pin 52 and each pivotally connected at their outer ends by a pivot pin 53 with a post connector or plug 54. As the braces for the sides and ends each pivotally connect with a post connector or corner plug 54, all the braces and

plugs are connected together as a unit which can be collapsed or folded up by slipping the retainer collars 55, similar to the collars 34 in structure and function, to a release position so that the links of each of the braces may be swung about their pivots 52 to a folded position. Each plug 54 has a cylindrical end 56 adapted to slidably fit in tubular end 57 of a corner post 58 and may be locked therein by a releasable detent 59 slidably mounted in the plug and urged outwardly to a position engaging an opening 60 in the post by a spring 61 as shown in Fig. 14. To permit the insertion of the plugs in the ends of the posts these posts are provided with slots 62 at right angles to each other to allow for passage of the pivot lugs 63 integral with each plug. The links 50 are similar to the links 30 previously described while the links 51 instead of being formed as a solid bar are formed as a channel bar similar to the link 50 but adapted to telescope within the same in the folded position of the links, and instead of a direct connection between the links of the posts they are pivotally connected to the corner plugs. The links 50 and 51 of each brace, however, when the plugs 54 are inserted in the ends of the posts, act in a manner similar to the links 30 and 31 to exert a spreading pressure on the sides of the container to hold it in an assembled stretched condition. In this form the braces at the bottom are disposed outside of the bottom 15 of the fabric body of the basket. It will be understood that the plugs 54 may be fixedly secured in the posts 58, if desired, since the pivotal connections 53 permit the folding of the braces together with the other parts of the structure when the collars 55 are moved to a released position.

As an alternative construction, which is shown in Fig. 15, the brace means may comprise links 64 formed of metal tubing either pivotally connected to the corner posts in a manner similar to the links shown in Fig. 12 or detachably connected to said corner posts by having their ends formed to engage in slots similar to the slots 29 shown in the first form and to permit ready collapsing of these brace means. They are each pivotally connected at 65 to a connecting link 66, and they are held in an extended straight line position by a tube or sleeve 67 adapted to slide over the ends of the adjoining tube 64 as shown in Fig. 15, and when this sleeve or collar 67 is slid back from the ends of one of the tubes and the connecting link 66, the other tubular part of the brace may be folded down and adjacent the first tube as shown in dotted lines in said figure. This permits the folding of the braces into a small space and in one form the folding of the braces with the fabric structure into a small compact unit.

To permit the carrying of the basket as a suitcase or bag, the flaps 19 may be provided with handles 68 adjacent their free edges as shown in Fig. 9.

In Figs. 16 and 17 I have shown certain modifications of the device where the same is used as an auto basket. The main basket structure is similar to those previously described and similarly numbered. The modification consists in making one of the end flaps 68 in the form of a flexible seat having a back 69, bottom 70, sides 71 and front 72 provided with leg openings 73. The sides 71 are provided with flap extensions 74 which may be turned over the top portion of the basket and be secured by snap fasteners 75 to the side walls 16 of the basket to suspend the seat

within the basket and above the bottom thereof. To prevent any tendency of the seat thus formed from shifting back straps 16 may connect the front portion of the seat with the end upper brace which may be of the form shown in Fig. 15 or Fig. 4. The straps 16 preferably have a detachable looped end connection 17 with the brace member. The basket structure may be hung against a seat of the automobile by cords (not shown) but similar to the cords 41 connected to the intermediate portions of the upper side braces and by hooks similar to the hooks 48 with the top of the seat.

With this construction the baby sits within the basket in the seat formed by the flap 68 with its legs projecting through the openings 73. When not in use, this seat forming flap 68 may be folded up against the end of the basket and be then secured in folded position either by straps 18 secured by snap fasteners 19 to the end wall of the basket as shown in Fig. 17 or by other suitable fasteners connecting the folded seat with parts of the end wall.

I desire it to be understood that this invention is not to be limited to any particular form or arrangement of parts except in so far as such limitations are included in the claims.

What I claim as my invention is:

1. A basket of the character described comprising a fabric container body having sides, end, and bottom portions, and corner post receiving pockets, corner posts mounted in said pockets, brace means extending between and in end thrust connection with said corner posts at the top and bottom portions of said body to hold the fabric body in stretched assembled condition, a fabric extension flap for one of the sides of said fabric body at the top thereof and coextensive therewith, and means for detachably connecting the free end of said flap to the top portion of the opposite side of said body at the upper edge thereof to form a bath table.

2. A basket of the character described comprising a fabric container body having sides, end, and bottom portions, and corner post receiving pockets, corner posts mounted in said pockets, and brace means extending between and in end thrust connection with said corner posts at the top and bottom portions of said body to hold the fabric body in stretched assembled condition, said sides having fabric extension flaps at the tops thereof and coextensive therewith, and flexible suspension means for connecting the free ends of said extension flaps together and hold them in a suspended condition to form a cover for said container.

3. A basket of the character described comprising a fabric container body having sides, end, and bottom portions, and corner post receiving pockets, corner posts mounted in said pockets, and brace means extending between and in end thrust connection with said corner posts at the top and bottom of said body to hold the fabric body in stretched assembled condition, said sides having fabric extension flaps at the top thereof and coextensive therewith, and flexible suspension means for connecting the free ends of said extension flaps together and hold them in a suspended condition to form a cover for said container, one end of said container having a fabric extension flap at the top thereof and coextensive therewith and adapted for positioning adjacent the covering side flaps to form a wind break.

4. A basket of the character described comprising a fabric container body having sides, end, and

bottom portions, and corner post receiving pockets, corner posts mounted in said pockets, and toggle link brace means extending between and in end thrust connection with said corner posts in the extended position of said links at the top and bottom portions of said body to hold the fabric body in stretched assembled condition, and connectors pivotally connecting together all of said toggle link brace means, the pivotal connectors for said toggle link brace means including plugs having removable connection with the ends of the posts.

5. A basket of the character described, comprising a fabric container body having sides, end, and bottom portions, and corner post receiving pockets, corner posts mounted in said pockets, and brace means extending between and in end thrust connection with said corner posts at the top and bottom portions of said body to hold the fabric body in stretched assembled condition comprising sets of toggle links and corner plugs, the links of each set being pivotally connected together at their inner ends and pivotally connected at their outer ends to opposite corner plugs, said corner posts having recesses in which said corner plugs are removably mounted, and means for locking each set of toggle links in an extended position.

6. A basket of the character described comprising a fabric container body having sides, end, and bottom portions, and corner post receiving pockets, corner posts mounted in said pockets, and collapsible brace means extending between and in end thrust connection with said corner posts at the top and bottom portions of said body to hold the fabric body in stretched assembled condition, said sides having fabric extension flaps at the top thereof and coextensive therewith and provided with rope receiving openings in their outer edges, and a rope for connecting the outer edges of said extension flaps together to form a cover for said body.

7. A basket of the character described comprising a fabric container body having sides, end, and bottom portions, and corner post receiving pockets, corner posts mounted in said pockets, brace means extending between and in end thrust connection with said corner posts at the top and bottom portions of said body to hold the fabric body in stretched assembled condition, said sides having coextensive extension flaps at the top thereof provided with rope receiving openings in their outer edges, a cover supporting rope extending through said openings to connect the outer edges of said extension flaps together to form a cover for said body, one end of said container having an extension flap at the top thereof provided with spaced rope receiving openings adapted to receive a portion of said cover supporting rope to position said end flap adjacent the flaps for the sides of said body to form a wind break.

8. A basket of the character described comprising a fabric container body having sides, end, and bottom portions, and corner post receiving pockets, corner posts mounted in said pockets, and collapsible brace means extending between and in end thrust connection with said corner posts to hold the fabric body in stretched assembled condition, said sides having extension flaps provided with handles centrally of and at their outer edge portions for carrying the basket in a suspended position.

9. A basket of the character described comprising a fabric container body having sides, end, and bottom portions, and corner post receiving

pockets, corner posts mounted in said pockets, brace means extending between and in end thrust connection with said corner posts to hold the fabric body in stretched assembled condition, one of the ends of said body having an extension flap in the form of a seat, means for suspending said seat within the container body from portions of said body and brace means and above the bottom of the same, said seat having leg openings in the front thereof.

10. A basket of the character described comprising a fabric container body having sides, end, and bottom portions, and corner post receiving pockets, corner posts mounted in said pockets, brace means extending between and in end thrust connection with said corner posts to hold the fabric body in stretched assembled condition, one of the ends having an extension flap formed to provide a seat having back, sides, bottom, and front portions, means for connecting the upper ends of the side portions to the sides of the container body over said brace means to suspend the seat within the container body above the bottom thereof, said front portion of said seat having leg openings therein.

11. A basket of the character described comprising a fabric container body having sides, end, and bottom portions, and corner post receiving pockets, corner posts mounted in said pockets, brace means extending between and in end thrust connection with said corner posts to hold the fabric body in stretched assembled condition, one of the ends having an extension flap in the form of a flexible seat, means for suspending the seat within the body from portions of said body and brace means above the bottom thereof, said seat when not in use being foldable against the end portion of the body, and means for holding the folded seat in its folded position.

12. A basket of the character described comprising a fabric container body having sides, end, and bottom portions, and corner post receiving

5 pockets, corner posts mounted in said pockets, brace means extending between and in end thrust connection with said corner posts to hold the fabric body in stretched assembled condition, one of said ends having an extension flap formed to provide a seat having back, sides, bottom, and front portions, the sides of said seat having extension flaps, means for detachably connecting said extension flaps over the top of said container body and to the sides thereof to suspend the seat within the body above the bottom thereof.
